6 Claims. (Cl. 51—231)

(Granted under the provisions of sec. 14, act of
March 2, 1927; 357 O. G. 5)

1

This invention relates to work supports for grinding and other machines in which the work is moved longitudinally relative to a tool, and has particular, though not exclusive, reference to work slides for grinding the blades of table knives, shear blades, and similar articles of cutlery.

It is usual to grind each side of table knife and similar blades as a separate operation, the grinding of one side being effected by feeding the blade, held edge upwards, lengthwise in an oblique (i. e., non-radial) direction across one side of a cup-wheel mounted on a spindle that is out of the normal to the direction of feed. The face of the wheel is hollow to form a conical surface, which, with the curvature of the face, imparts the desired slightly rounded face to the side of the blade. The blade is first fed inwards clear of the wheel, and is then moved into contact with the wheel to begin grinding at the "neck" of the blank adjacent the bolster, and is then withdrawn outwardly slowly still in contact with the face of the wheel until the blade tip has been ground, the blade being twisted slowly about an axis substantially parallel to its length during withdrawal to adjust the taper of the blade to the lessening thickness of the blade from bolster to tip. For grinding shear and other blades having a flat or slightly hollow-ground side, and for grinding blades of different length, the work slide is adjustable as to obliquity as well as to stroke, and the provision for presenting and retracting the blade has in consequence usually been by way of a mechanism that is both cumbersome and slow to operate.

An object of the invention is to present a blade to the wheel and hold it to a definite path during the grinding stroke.

Another object is to provide a mechanism in which there is not only little likelihood of wear, but also negligible effect of wear on the accuracy of the path followed during the grinding stroke.

A further object is to enable the blade to be retracted quickly and automatically at the end of the grinding stroke.

Further objects include the provision of simple adjustment of stroke in accordance with the length of the blade to be ground.

The invention comprises a work support including a table longitudinally-movable with respect to a tool, a work slide carried by the table and guided so as to be able to slide transversely of the table, a stop adapted to be encountered near the end of one movement of the table, cam-means operable by the stop to move the slide transversely

of the table, and a further stop adapted to be encountered near the end of the reverse movement of the table to effect a return movement of the slide transversely to the table. The work may be operated on by a grinding wheel, milling cutter, or the like, but in the following description, reference will be mainly to the use of a wheel for grinding the work.

Preferably, the cam is carried by a push-rod
10 movable longitudinally of the table and adapted to engage the first stop, the cam surface engaging a follower on the work slide. The push-rod may, in addition to providing the lift required to move the slide the desired amount trans-
15 versely of the table, provide a locking surface, which, by continued movement of the push-rod relative to the table, prevents return movement of the slide, thus dispensing with separate locking mechanism. The second stop returns the
20 push-rod to release the slide, the return of the slide preferably being effected by a spring en-
25 ergised during the movement of the slide under the cam-action. The spring serves to hold the slide firmly against the locking surface of the
30 push-rod, which has long bearing surfaces engag-
35 ing corresponding surfaces in the work table (e. g. in one side of a slot in which the push-rod slides) and thus provides a rigid support for the positioning of the work slide while the latter is carrying the blank in grinding contact with the
40 wheel. When the push-rod is returned by the second stop, the spring moves the slide quickly away from the wheel.

Although the use of a push-rod with a cam to
35 move the slide transversely of the table enables the slide to be moved in any desired direction across the table, it is preferred to mount the slide on guides inclined across the table, so as to provide, for any given width of table, guiding
40 surfaces longer than the width.

The invention will now be described in greater detail with reference to a grinding machine in which the cam-action for moving the slide trans-
versely to the table is provided by a push-rod.

45 In the accompanying drawings

Figure 1 is a plan view, partly in section, of a grinding machine set for the grinding of table and similar knives;

Figures 2, 3, and 4, are views similar to Figure 1
50 at different stages in the operating cycle;

Figure 5 is a plan view of the work slide and moving table in greater detail and to a larger scale; partly in section;

Figure 6 is a sectional elevation taken on the
55 line 6—6 of Figure 5;

Figure 7 is an end elevation of Figure 6, showing also the work holder;

Figure 8 is a fragmentary section on the line 8—8 of Figure 5;

Figure 9 is a large-scale section through the blade of a knife in the work holder, the section being taken on the line 9—9 of Figure 4;

Figure 10 is a similar view to Figure 9, but looking in the reverse direction, showing how the blank is held on the work-holder;

Figure 11 is an elevation on the line 11—11 of Figure 10; and

Figure 12 is a diagram showing the approach of the blank to the wheel.

Referring particularly to Figures 1 and 7, a table 12 is mounted on long slide ways 13 carried by the machine bed 14 so as to be movable to and fro in a direction generally transverse to the axis 15 of a cup wheel 16.

A work slide 17 is carried on the upper face of the table 12, and to it is secured an angle bracket 18, from which pivot brackets 19 protrude towards the wheel 16 to receive pivot pins 20 at each end of a work holder 21 comprising a long block 22 to the face of which is secured a pad 23. Below one end of the pad, a ledge plate 24 protrudes to support the back edge of a knife blade 25 near the bolster 26, the tang 27 of the blade being engaged in a bayonet slot 28 (Figures 10 and 11) of a pin 29 protruding from the block 22. An arm 30 of the work support 21 carries a roller 31 resting on a former bar 32, adjustable (as will be described later) to twist the support 21, if desired, slowly about the pivots 20 as the support is carried by the table 12 across the wheel 16.

The axis 15 of the wheel 16 is shown inclined (at about 10°) to the normal to the path of the table 12, and the face 33 of the wheel is inclined inwards to the same amount so as to lie parallel to the path of the table. For some purposes the axis may be normal or inclined in the opposite direction to the normal, but in all cases the movement of the table 12 of the machine shown is used to carry the work across the left-hand side 34 of the wheel, with an idle movement in one direction and a grinding movement in the reverse direction.

The machine may, however, be constructed with the table and work-holder reversed with respect to the wheel, in which case the work is carried across the right-hand side of the wheel, to enable the other side of a blank to be ground; and, in fact, machines are generally used in pairs, one left-hand and one right-hand.

Referring now to Figures 5, 6, and 7, it will be seen that the table 12 has two V-grooves 35 running at 45° from right to left from the front to the back of the table, and the slide 17 has two corresponding but inverted grooves 36. In the grooves 35, square-sectioned blocks 37 are secured by screws 38, and the slide 17 is held on to the blocks 37 by washers 39 retained by lock nuts 40 on pins 41 projecting from the table 12 and passing through slots 42 in the slide parallel to the grooves 35, 36. A plunger 43, also parallel to the grooves 35, 36 is urged by a spring 44 into contact with an abutment 45 protruding from the table 12 so as to urge the slide 17 towards the front of the table 12.

A hydraulic cylinder 46 carried by the machine bed 14 runs parallel to the length of the table 12 and the piston 47 is connected by a piston rod 48 to a lug 49 projecting downwardly from the right-hand end of the table 12. Oil admitted to one or other of the ports 50 in turn, through

pipes 51 connected to suitable reversible valve-gear (not shown), causes the table to move to and fro with any desired length of stroke.

Running lengthwise of the table 12 is a parallel slot 52, passing to the right-hand end of the table and breaking through a recess 53 near the middle of the table. A push-rod 54 closely fits the slot and a lateral arm 55 of the rod protrudes through the recess 53 beyond the front of the table. Opposite the arm 55, the rod is notched at 56 to form a land 57 leading by a cam slope 58 to the edge 59 of the rod. A follower roller 60 depends from a pin 61 secured to the slide 17 into the recess 53 and is urged into the notch 57 by the plunger 43, so that the roller is forced into contact with the rod 54.

The end of the rod 54 carries a plate 62 facing an adjustable stop 63 on a bracket 64 extending upwards from the machine bed 14. The plate 62 itself carries an adjustable stop 65 facing the edge of a cover plate 66 secured to the table 12 over the rod 54. An adjustable stop 67 carried by a bracket 68 from the machine bed 14 lies parallel to the length of the table 12 in line with the lateral arm 55 of the rod 54.

The sequence of operations is shown in Figures 1—4:

In Figure 1, a knife blade 25 in the work holder 21 is moving to the right under the admission of oil through the left-hand port 50 of the cylinder 46. The roller 60 bears on the land 57 in the notch 56 of the push-rod 54, the slide 17 thus lying in its nearest position to the front of the table 12. In this position, the blade 25 lies clear of the side 34 of the wheel 16.

As the table 12 nears the right-hand end of its stroke the plate 62 on the end of the push-rod 54 meets the stop 63, and the push-rod is prevented from further motion to the right. The table 12 continuing its motion to the right, the roller 60 is caused to ride up the cam slope 58 of the now-stationary rod 54 and on to the edge 59 of the rod. The slide 17 carrying the roller 60 is forced to follow the movement of the roller, and is thus pushed towards the rear of the table 12, by an amount equal to the lift of the cam, the slide moving along the guide blocks 37 in the grooves 35, 36. During this movement, the spring 44 is compressed on to the plunger 43.

On reaching the full lift of the slope 58, the roller 60 comes to rest on the edge 59 of the bar 54, and remains urged against the bar by the pressure of the plunger 43, the whole length of the bar resting in the slot 52 providing a rigid backing against the thrust of the slide 17 transversely of the table 12.

When the cover plate 66 reaches the stop 65, the right-hand motion of the table 12 ceases, and at this moment the outside diameter of the wheel 16 makes grinding contact at the "neck" of the blade 25, i. e. against the bolster 26, the blade having been brought against the face of the wheel by the movement of the slide 17 to the rear of the table 12. This is the position shown in Figure 2. The operation of the cylinder 46 reverses, and the table 12 moves to the left, carrying with it the slide 17, which is locked to the table by the pressure of the roller 60 on the edge 59 of the rod 54.

The movement of the work up to this point may be closely followed by reference to Figure 12:

The blank (blade 25, bolster 26, and tang 27) as shown in full lines is moving to the right (arrow a) as in Figure 1, with the blade 25 parallel to, but clear of, the face 33 at the left-hand

side 34 of the wheel 16. When the push-rod 54 is held by encountering the stop 63, the table 12 continues to move by the amount shown by the chain-line containing the arrow b, and the cam 58 pushes the slide 17 (and therefore the blank) in a 45° direction as shown by the chain-line containing the arrow c. The component of the table movement and the slide movement is thus a movement along the broken line containing the arrow d.

The blank has now reached the position (corresponding to Figure 2) shown in broken lines (25^a, 26^a, 27^a) the blades 25^a having one side in contact with the face 33 of the wheel, and the "neck" 26^a lying against the radiused edge 16^a of the wheel, as may be adjusted with precision by means of the stop 63. At this point, the table 12 is reversed by the cylinder 46 (arrow e), and grinding of the side of the blade 25^a continues from the completed neck to the tip of the blade 20 until the position of Figure 3 is reached.

During the grinding stroke, the pressure of the wheel keeps the rear side of the blade firmly against the pad 23, with the back edge of the blade resting on the ledge 24. The accurate guiding of the table 12 by the long slide ways 13 and the pressure of the spring 43 through the slide 17 to the long edge of the slot 52 containing the push-rod 54 ensures that the blade follows an accurate line across the wheel 16, which may be repeated with equal accuracy if it prove necessary to send the blade a further time across the wheel. As a result, a highly finished ground surface is produced that calls for the minimum amount of glazing in a subsequent operation, as is usual with table and similar knives.

When the position in Figure 3 is reached, the stop 67 meets the arm 55 to push the rod 54 to the right (relatively to the moving table 12), thus carrying the cam slope 59 under the roller 60. The pressure of the plunger 43 causes the roller 60 to push the rod 54 to the right (there being nothing to oppose this movement of the bar), and the roller 60 reaches the land 57 with a snap action. The slide 17 thus moves quickly towards the front of the table 12 (Figure 4), and the blade 25 is withdrawn from the wheel, with no delayed contact that might mar the ground surface of the tip of the blade.

In a short continued motion of the table 12 to the left (Figure 4), the ground blade is removed and replaced by a fresh blank, or, if necessary, the blade is left to undergo a further grinding cycle. Reversal of the operation of the cylinder 46 again brings the mechanism to the position shown in Figure 1. The width of the recess 53 provides the necessary freedom of movement of the arm 55 relative to the table 12, the right-hand side of the recess limiting the amount by which the push-rod moves relatively to the table. The three stops 63, 65, and 67 enable the positions of the ends of the strokes and the rearward and forward movements of the slide 17 to be determined with precision in accordance with the length of the blade 25, in conjunction with the reversing mechanism for the supply of oil to the cylinder 46.

As the slide 17 is carried to the left, the roller 31 moves along the former plate 32. This plate is adjustable about a pivot 69 (Figure 7) on a stem 70 by a setting screw 71, out of line with the pivot 69, and is clamped by a nut 72 in adjusted position. The stem 70 is carried in a tubular mounting 13 on the machine bed 14, and

is adjustable for height by a screw 74 and for angle by a screw 75.

For grinding table and similar knives, the plate 32 is set, by the adjustments just described, to twist the work holder 21 steadily and slowly as grinding proceeds from neck to tip, to allow for the varying taper of the blade arising from the gradual thinning of the back edge of the blade in the direction of the tip. The slight outward curvature of the section of the blade (indicated in Figure 9) arises from the presentation of the face of the blade to the cup wheel along a line that does not intersect the axis of the wheel, and from the inward inclination of the face of the wheel.

During the whole stroke, the blade remains pressed to the pad 23 by the pressure of the wheel 16, and the blade is solidly supported by the thrust carried through the roller 60 and push-rod 54 to the table 12, and thence to the long slide ways 13. There is little likelihood of wear in these parts, and should wear take place, the steady pressure towards the front of the machine ensures that the work follows a straight and consistent path across the wheel.

When one side of a blade has been ground in a machine as in Figure 1, the other face is ground in a machine with the parts reversed; the blank being inserted at the right and ground by the right-hand side of the wheel.

For grinding other forms of cutlery, the axis of the wheel may be normal to the direction of motion of the table, the side of the blank then being ground perfectly flat, or it may be reversed in inclination (as compared with Figure 1) to produce a hollow-ground surface, e. g. for shear blades. Though these different positions of the axis of the wheel relative to the table may be fixed in any one machine, it will be evident that they may be provided in a single machine by pivoting the whole of the part of the machine bed carrying the slide way, table, work slide, cylinder, stops, and associated mechanism in relation to the wheel, the position of the pivot being substantially in line with the operative portion of the face of the wheel, as indicated at 76 in Figure 1. Alternatively, the wheel-mounting may be adjustable about a similarly-positioned pivot.

Figures 10 and 11 show how the blade 25 is held against the pad 23 and on the ledge 24. A screwed shank 77 secures the pin 29 protruding from the block 22 of the work support beyond one end of the pad 23. The pin has the inclined slot 28 in its face breaking into a hole 78 parallel to the length of the pad 23, the slot 28 and the hole 78 forming a bayonet joint. The tang 27 is passed through the slot 28 with the blank inclined at a corresponding angle, and when the tang enters the hole 78, the blank is able to drop parallel to the pad 23 until the back edge rests on the ledge 24, there being sufficient freedom of the tang in the hole 78 to permit the blade 25 to be pressed by the wheel against the pad 23.

The machine has been described with the wheel axis 15 horizontal, and the work movable in a horizontal direction towards and away from the wheel, but it will be understood that the wheel may be mounted otherwise than horizontally; thus it may have a substantially vertical axis, and the work slide may be arranged to move the work towards and away from the wheel in a vertical direction.

The work support may be used in other ma-

chines with a to-and-fro movement of the work, e. g. milling machines and planing machines.

What we claim is:

1. In a grinding or other machine, a machine bed, a table movable longitudinally on the bed with respect to a tool, hydraulic means to impart a longitudinal stroke to the table, a work slide carried by the table and guided so as to slide transversely of the table, a push-rod movable with the table and having a positively limited movement longitudinally of the table, a cam on the push-rod adapted to move the work slide transversely of the table during such limited movement, stops on the bed to engage the push-rod near the ends of its movement with the table, and an adjustment for at least one of the stops to provide any length of stroke of the table within the maximum stroke of the hydraulic means after allowing for the limited movement of the push-rod, the positive engagement of the push-rod with the table at the ends of such limited movement determining the stroke of the table against the urge of the hydraulic means.

2. In a grinding or other machine as in claim 1, an arm projecting laterally from the push-rod, one of the stops being positioned to one side of the push-rod to engage the arm.

3. In a grinding or other machine as in claim 1, a recess in the table, and an arm on the push-rod projecting laterally through the recess, one of the stops being positioned to one side of the

push-rod to cause the arm to perform its limited movement determined by engagement of the arm with one side of the recess.

4. In a grinding or other machine as in claim 1, means for adjusting one end of the limited movement of the push-rod independently of the stops effecting such movement.

5. In a grinding or other machine as in claim 1, guides inclined across the table, and a spring urging the work slide along the guides in opposition to the cam on the push-rod.

6. In a grinding or other machine as in claim 5, inclined V-grooves in the table, square-sectioned blocks secured in the grooves to form guides, and registering inverted grooves in the work slide.
